UNITED STATES PATENT OFFICE.

OLIVER E. BECKER, OF OAK PARK, ILLINOIS.

MEANS FOR MAKING ELECTRICAL BRUSHES.

1,319,751.

Specification of Letters Patent. Patented Oct. 28, 1919.

Original application filed April 13, 1918, Serial No. 228,377. Divided and this application filed November 8, 1918. Serial No. 261,679.

To all whom it may concern:

Be it known that I, OLIVER E. BECKER, a citizen of the United States, residing at Oak Park, in the county of Cook and State 5 of Illinois, have invented a certain new and useful Improvement in Means for Making Electrical Brushes, of which the following is a full, clear, concise, and exact description, reference being had to the accompanying drawings, forming a part of this 10 specification.

My invention relates to brushes for electrical machinery and means for making the same.

15 More particularly my invention relates to gauze brushes, that is, brushes made of interwoven or interlaced wires, and means for attaching the leads or pigtails to the same.

20 This present application is a division of my co-pending application, Serial Number 228,377, filed April 13, 1918.

As is well known to those skilled in the art, the body of the gauze brush is generally constructed by rolling or winding a sheet or strip of wire gauze upon a mandrel and then removing the roll from the mandrel and pressing or rolling the gauze into suitable prismatic form. This is set 25 out in the patent to Guttman, No. 599,781.

The general practice of finishing the gauze brush and attaching the lead or pigtail has heretofore consisted in dipping the upper part of the brush in tin or solder to 30 fill the parts of the same for holding the form of the brush and for forming a suitably rigid portion for the attachment of the lead or pigtail. A hole is then drilled into the upper part of the brush and the lead 35 or pigtail, which is usually made of stranded cable or woven ribbons, is then soldered into said hole.

I have found this to be unsatisfactory for a number of reasons. One objection is the 40 amount of labor involved. A further objection has been due to the fact that heating of the brush may result in loosening of the lead from the body of the brush, and at any event it may easily result in increasing the contact resistance between the lead and the body of the brush. A further and more frequently encountered objection 45 is the tendency of the solder to be taken

up by the cable or lead by the capillary action of the solder upon the strands of the 50 cable, thereby rendering the lead stiff. If the lead becomes filled with solder it becomes practically rigid and tends to interfere with the action of the brush in the holder and may easily be broken off by 55 bending.

The object of my invention is to provide mechanism especially arranged and adapted for practising my improved method of making brushes and producing my improved brush as described and claimed in my said copending application. According to my invention I take the brush body after it is roughly formed and compress the same into suitable shape, leaving a part of 60 the brush body where the lead is to be attached in a relatively loose condition. I drive a spreading punch in the form of a pointed pin into the uncompressed portion to form a hole, somewhat according 65 to the manner in which an awl is forced into a piece of leather or fabric. The spreading punch preferably does not form the hole by shearing or punching, in the sense of driving the metal downward, but 70 preferably spreads the fibers, and incidentally tearing the same apart laterally. This leaves an enlarged portion in the body 75 of the brush about the hole. The body of the brush with the hole formed in the 80 enlarged portion may then be dipped to fill the top surface with solder so that the brush may better retain its form. This latter step may, under certain conditions, be omitted. Thereafter the lead or pigtail 85 is inserted in the hole and the body of the brush about the hole is then crushed together upon the end of the lead or pigtail.

The crushing of the body of the brush 90 upon the pigtail causes the individual fibers or wires of the gauze to grip the individual fibers of the lead or pigtail very firmly. Thus the intermixing and interlacing of the strands of the wire or gauze on the strands 95 of the flexible lead, forms an ideal gripping engagement for holding the pigtail or lead to the body of the brush.

This present application has to do especially with the novel die apparatus 100 which I have devised for forming the

brush, preferably arranged to form the hole for the pigtail in the same operation which forms the brush.

The brush having been pressed into shape 5 in the dies and the hole formed for the pigtail, a lead is then inserted by hand. The steps of closing the hole upon the lead and bringing the brush to final form is then performed by another die operation.

10 Thus not only do I provide a less expensive method of constructing the finished brush, but I provide also an improved and better article and further I provide a convenient means for performing certain steps 15 of the method above outlined. This method may be practised with plain gauze brushes or with the lubricated brush described and claimed in patent to Schweitzer, No. 1,228,484.

20 My improvement in brush making dies will be more readily understood by reference to said drawings, wherein I have illustrated a preferred form thereof and in which,

25 Figure 1 is a vertical sectional view taken on the line 1—1 of Fig. 2 of the die mechanism employed to form the brush;

Fig. 2 is a horizontal sectional view taken on the line 2—2 of Fig. 1, showing certain 30 of the parts in plan;

Fig. 3 is a vertical section taken at right angles to the section of Fig. 1 on line 3—3 of Fig. 1;

Fig. 4 is an elevational view of the finishing die mechanism;

Fig. 5 is a perspective view of the roll of gauze prior to its formation into rectangular form;

Fig. 6 illustrates the roll of gauze as compressed into rectangular prismatic form, with the hole and enlargement formed at one corner;

Fig. 7 illustrates the body of the brush after the operation of dipping the top of 45 the brush in melted metal;

Fig. 8 is a sectional view of the body of the brush showing the manner of securing the union between the fibers of the gauze and the strands of the lead;

Fig. 9 is a perspective view of the body of the brush after the same has been dipped and the pigtail or lead inserted in the hole;

Fig. 10 shows the dies for corrugating the sides of the gauze brush; and

Fig. 11 is a perspective view of a brush with corrugated sides for strengthening the outer layer against spreading.

As previously explained, the first step in producing a brush is to form a roll of gauze 60 by rolling a strip or sheet of the same upon a mandrel to produce a rough roll as shown in Fig. 5.

This feature is old and is explained in the prior patents above referred to. The roll of 65 gauze 1, which later forms the body of the

brush, is placed in the die mechanism shown in Figs. 1, 2 and 3 and is there brought to form and is punched by means of a spreading punch by the mechanism which will now be described. The roll 1 70 may be given a preliminary shaping operation before placing in the die mechanism shown in Figs. 1, 2 and 3 or it may be placed in the die mechanism in the rough. In Figs. 1, 2 and 3 I have shown the roll 1 as having 75 a preliminary shaping to bring it to substantially rectangular form, although as above explained this is not a necessity. The roll 1 is rested against a back plate member 2, this back plate being bolted by means of 80 the bolts or cap screws 3 upon the back frame member 4, mounted upon the main frame plate 5. The main frame plate 5 in turn is supported upon a suitable pillow block 6 of any desired weight and configuration.

The back plate 2 has a pair of stop members or projections, 6 and 7. Movable end die members 8 and 9, which are suitably cut out to receive the projections 6 and 7 as 90 shown at 10 and 11, are guided between the back plate 2 and the front plate 12. The end die members 8 and 9 are provided with projecting ends 13 and 14 which are adapted to engage the end parts of the roll of gauze 95 1. At their rear ends the end die members 8 and 9 rest against the stops 15 and 16, which stops are rigidly connected to the main frame plate 5. The retracting rods 17 and 18 are slidably mounted in the blocks 100 15 and 16 and at their inner ends are threaded to, or otherwise secured to the end die members 8 and 9. Suitable springs 19 and 20 are interposed between the blocks 15 and 16 and the head members 21 and 22 on 105 the rods 17 and 18, so that when the die members are moved inwardly to operate upon the roll of gauze 1, they may be automatically retracted by means of the springs 19 and 20.

A front die member 23, guided in a suitable frame 24, is adapted to move in and press upon the front side of the roll of gauze 1. A retracting rod or plunger 25 and the spring 26, serve to retract automatically the 115 die member 23, as will be set out below.

A guiding plate 27 extends over the die members 8 and 9 and also extends over the side die member 23 to prevent accidental disengagement of the die members by upward motion. This guiding plate 27 normally extends across the die member 23, but is shown as broken away in the figures for the sake of clearness. The guide plate 27 is secured on the top of the front plate 12. 125

It will be noted that the die members 2, 8 and 23 have recesses 28, 29 and 30 formed in the same so that the roll of gauze 1 may spread into the same to form an enlargement. This is for the purpose of permitting 130

the gauze to be spread to form a hole in the same for attaching the lead as will be described later.

The end die members 8 and 9 are adapted to be moved inward by the vertical cam pieces or punches 31 and 32, which are fastened in the head member 33. The head member 33 is connected in the end of the plunger of the punch press, as is well understood by those skilled in the art. The vertical cam or punch members 31-32 are provided with the camming shoulders 34 and 35, these shoulders being adapted to engage the tapered or inclined surfaces 36 and 37 on the end die members 8 and 9 to force the same toward each other when the punch members 31 and 32 descend.

The front die member 23 is similarly provided with an inclined shoulder 38 adapted to be engaged by the shoulder 39 of the vertical cam or punch member 40, which is also fastened in the head member 33.

The timing of these punches is such that the punch 40 preferably closes in its die member 23 against the body 1 first. The end punches 31 and 32 then close in the end dies 8 and 9 to compress the roll of gauze 1 into substantially finished shape and size with the exception of the enlargement formed in the recesses 28, 29 and 30 of the adjacent die members. Thereafter the roll of gauze is operated upon by a spreading punch 42, which consists of a short pointed pin fastened in the bar 43. The bar 43 is in turn secured by means of a suitable shank 44 in the head member 33.

The roll of gauze 1 is thus transformed into the formed brush body 45, which has an enlargement 46 to receive the metal of the gauze, which is spread apart or moved laterally by the formation of the hole 47. It is to be noted that the opening 47 extends only a short distance down into the body of the brush and also the enlargement 46 extends down only a short way.

Thereafter the top of the brush body 45 may be dipped in tin or solder to unite the upper strands of the gauze, as indicated at 48 in Fig. 7. Thereafter the stranded lead 49, the upper end of which may be attached to a suitable clip 50, is inserted in the opening 47 and the body of the brush with the pigtail or lead 49 in place, is then placed in a suitable closing die 51 and is pressed by the plunger 52 to compress the material of the body of the brush upon the lead 49 and at the same time forming the brush to finished size. It is to be noted that the gauze of the brush may be formed with the fibers thereof running parallel with the edges of the finished brush, or may run diagonal thereto, the resulting brush being securely gripped to the lead by the mechanical action alone.

It is to be noted that the spreading punch

42 tends to spread and may break some of the fibers of the gauze and when the gauze is compressed about the lead, these ends form effective gripping fingers for engaging the strands of the lead 49 so that a secure fastening is provided.

I contemplate the use of plain gauze or lubricated gauze of the character set out in the prior patent to Schweitzer above mentioned.

The body of the brush may be treated as set out in my co-pending application, Serial Number 221,665, filed March 11, 1918, to prevent spreading of the layers of gauze and fraying of the ends. I have also discovered that the brush may be reinforced by mechanical formation, as shown in Figs. 10 and 11. By means of the die 54 and the punch 55, indentations or corrugations 56 may be formed in the material of the brush to provide mechanical reinforcing ribs. This corrugation of the sides may be secured at the time that the brush is formed in the operations illustrated in Figs. 1, 2, and 3, or it may be performed in a closing operation when the material of the brush is compressed about the lead 49 as shown in Fig. 10.

I do not intend to be limited to the specific structures herein shown and described and I intend that certain modifications thereof, such as will be apparent at once to those skilled in the art, shall fall within the scope of the appended claims.

I claim:

1. An apparatus for forming a gauze brush of the character described, said apparatus including die members for engaging and compressing the body of the brush, said members being provided with recesses to avoid compression of the body of the brush at the point where the lead is to be attached.

2. In a die mechanism of the kind described, pairs of coöperating die members for engaging the lateral sides of the body of a gauze brush, means for moving the dies in pairs into engagement with opposite sides of the brush, said dies having coöperating recesses preventing the compression of the brush at the point where the lead is to be attached.

3. In a die mechanism of the kind described, coöperating flat faced die members for engaging the lateral sides of a gauze brush, means for relatively moving said members to form and compress the body of a brush, said members having recesses to form an enlargement in the brush at the point where the lead is to be attached.

4. In a die mechanism of the kind described, coöperating flat faced die members for engaging the lateral sides of a gauze brush, means for relatively moving said members to form and compress the body of a brush, said members having recesses to

form an enlargement in the body of the brush at the point where the lead is to be attached, and a pointed spreading punch adapted to be forced into the enlarged part 5 of the brush while same is held in said die members.

5. In a die mechanism of the kind described, pairs of die members for engaging the lateral sides of a gauze brush, cam means 10 for moving said dies in pairs to form a gauze brush, said dies having coöperating recesses for forming an enlargement on the brush at the point where the lead is to be attached, and a pointed spreader punch 15 adapted to be projected into said enlargement to spread the wires of the brush and form an opening for receiving a lead.

6. The herein described improvement in die mechanism, comprising die members for 20 engaging the lateral sides of a gauze brush, means for moving said members in pairs for compressing a brush, said die members provided with coöperating recesses for forming an enlargement on the compressed brush at 25 the point where the lead is to be attached, and means for spreading the wires of the brush at said enlarged part while the brush is held between said die members, for making a hole to receive a lead.

30 7. In a die mechanism for making gauze brushes, die members for engaging the lateral sides of a brush, means for moving said dies in pairs into engagement with opposite sides of the brush, said dies having recesses 35 for permitting the formation of an enlargement in the body of the brush as the dies close upon the brush, at the point where the lead is to be attached, a pointed spreading punch attached to said die moving means

and adapted to be thrust into the enlarged 40 part of the brush to provide a hole for the insertion of a lead.

8. The herein described improvement in dies for compressing a wire gauze brush, 45 said dies having coöperating recesses for forming an enlarged uncompressed part in the brush at the point where the lead is to be attached, means for spreading the wires of the brush body at said enlarged part to provide a hole for the reception of a lead 50 wire, and means for compressing the enlarged part to engage a lead inserted in said hole.

9. The herein described improvement in dies for compressing a wire gauze brush, 55 said dies having coöperating recesses for forming an enlarged uncompressed part in the brush at the point where the lead is to be attached, means for spreading the wires of the brush body at said enlarged part to 60 provide a hole for the reception of a lead wire, and transverse ribs on said dies for corrugating the flat faces of the brush.

10. The herein described improvement in dies for compressing a wire gauze brush, 65 said dies having coöperating recesses for forming an enlarged uncompressed part in the brush at the point where the lead is to be attached, means for spreading the wires of the brush body at said enlarged part to 70 provide a hole for the reception of a lead wire, and transverse ribs on some of said die members for forming transverse grooves in the flat faces of the brush.

In witness whereof, I hereunto subscribe 75 my name this 5th day of November, A. D. 1918.

OLIVER E. BECKER.
